UNITED STATES PATENT OFFICE

JOHN K. GOIN, OF UNIVERSITY CITY, MISSOURI

FORM OR MOLD FOR CONCRETE

Application filed January 16, 1929. Serial No. 332,817.

This invention relates to forms or molds for the formation of concrete structures such as conduits, bridges and other hollow devices.

An object of the invention is to provide a form or mold comprising a series of angular mold sections assembled to provide a form or mold that is polygonal in end elevation or cross section, in combination with mechanism for moving said sections radially from a common axis and at the same time bracing and strengthening the overlapping portions of said sections.

Another object of the invention is to provide a form or mold of the type and character mentioned including means for forming and shaping the exterior surfaces of the polygonal conduits, bridges and hollow structures.

Other objects will appear from the following description, reference being made to the drawings in which I have shown different embodiments of the invention and in which,

Fig. 1 is an end elevation of a preferred embodiment.

Fig. 2 is a cross sectional view approximately on the line 2—2 of Fig. 1.

Fig. 3 is a cross sectional view on the line 3—4 of Fig. 2 showing the form or mold extended to its capacity.

Fig. 4 is a cross sectional view on the same line showing the form of mold reduced to smaller dimensions.

Figs. 5 and 6 are cross sectional views taken on the line 5—5 of Fig. 2, Fig. 5 showing the form or mold of reduced size, and Fig. 6 showing the said form or mold extended.

Figs. 7 and 8 are sectional views showing a modified type of expanders for the mold sections.

The wall of the form or mold comprises a series of angular metallic sections of a length sufficient to form and complete the conduit, bridge or other hollow device. Each angular metallic section comprises a part 1 and a part 2 integrally connected and extending at right angles to each other. These wall members are assembled and maintained in a relationship in which a form or mold approximately square in cross section is provided, although it is obvious that the device

may be varied in this regard, if desired. The parts 1 and 2 of each wall member lap the adjacent parts of the corresponding wall member in sliding relationship.

Longitudinally in the corner of each wall member an angular bar 3 is secured. These bars 3 are of sufficient strength and rigidity to prevent damage to the wall members which may be, and preferably are, composed of sheet metal shaped in the form shown and described. An angle bar 4 is attached to the inner side of each wall member that is lapped on its outer side by an adjacent wall member. The bars 3 and 4 preferably extend the full length of the device so as to obtain the necessary strength and resistance to the weight of the concrete. A shaft 5 extends longitudinally and axially through the device and has fixed thereon at spaced intervals gears 6 and 7. Expander racks 8 have their outer ends pivoted to the bars 3 and their inner portions meshing with the gears 6. Brace racks 9 have their outer ends pivoted to the bars 4 and their inner portions meshing with the gears 7. The gears 6 and 7 are between spaced plates 10 which function to guide and prevent the racks from becoming laterally disengaged from the gears. The plates 10 do not rotate with the shaft 5. Said plates support between them guides 11 which hold the respective racks in mesh with the respective gears 6 and 7. These plates are all rigidly connected by tie rods 10^a extending longitudinally from end to end of the device.

There is one set of these expanders 8 and these braces 9 near each end of the device and there may be others at intervals along the length of the form or mold.

The disc 10 at one end of the mold supports a bracket 12 in which a worm 13 is journaled for rotation, being provided with a polygonal axial extension 14 for engagement with a crank or similar operating device. The worm 13 meshes with a gear 15 on the shaft 5. Obviously, rotation of the worm will rotate the shaft 5 and thereby the gears 6 and 7 to operate the expanders 8 and the braces 9 to expand and to contract the form or mold. The difference in extent of radial

movement of the portions of the mold sections and the overlapping portions of said sections is taken care of by looseness of the mesh of the gears with the racks. This is made possible because the extent of expansion and contraction is about four to six inches, more or less.

In order to assist in determining the proper thickness of the walls I provide auxiliary sections 16 adapted to seat against abutments 17 on the ends of rods 18. These rods 18 operate through collars 19 on arms 20 which swing from the shaft 5. Set screws 21 in the collars 19 are adjustable to hold the rods 18 in their different adjustments so as to permit positioning of the sections 16 at any desired distance away from the wall of the form or mold. The walls 16 may be of sheet metal, as indicated by dotted lines in Fig. 2, or of wood, as shown in Figs. 3 and 4.

In the variation of the invention shown in Figs. 7 and 8 racks 22 have their outer ends pivotally connected with angle bars 23 in the corners of the mold wall sections 24 by links 25. These racks 22 mesh with gears 26 on the shaft 27 and are guided by fixed guides 28 supported by the discs 29 between which the gears 26 are located. In this form of the invention the bracing racks 30 have their outer ends pivoted to bars 31 attached to the overlapping portions of the wall sections 24 and mesh with gears 32 on the shaft 27 and are guided by guides 33 attached to the discs 29 between which the gears 32 are located. This form of the invention is operated in the same way to expand and contract the form or mold as previously described.

In using the device to form conduits, bridges, etc., a bottom layer of concrete is first deposited and the form or mold placed thereon in proper adjustment. The auxiliary sections 16 are properly adjusted beyond the sides of the form or mold and the space between said auxiliary sections and the sides of the form or mold are filled with concrete. The upper edges of the auxiliary walls 16 extend to the height to which it is desired to build the conduit or bridge so that the concrete may be poured also upon the top of the form or mold, as will be understood by reference to Fig. 4. The upper edges of the auxiliary walls 16, therefore, constitute guides or gages to indicate to the workmen the height to which the concrete should be poured. After the concrete has hardened and solidified sufficiently, the form or mold is contracted and withdrawn from the work. Also, the auxiliary walls 16 may be loosened and removed.

I am aware that there may be other changes and modifications within equivalent limits without departure from the nature and principle of the invention.

What I claim and desire to secure by Letters Patent is:—

1. A form comprising a series of angular wall sections assembled in approximately rectangular form and each having one edge lapping the edge of an adjacent section, a rotary shaft, series of gears attached to said shaft, series of racks having their outer ends pivotally connected with the corners of said wall sections respectively and having their inner portions meshing with corresponding ones of said gears, another series of racks having their outer ends pivotally connected with the lapped portions of said wall sections respectively and having their inner portions meshing with corresponding ones of said gears, guides for all of said racks, and mechanism for rotating said shaft and thereby said gears to move said racks longitudinally and thereby move said wall sections outwardly and inwardly and support said wall sections from distortion in all positions thereof. 75 80 85

2. A form comprising a series of angular wall sections assembled in approximately rectangular form and each having one edge lapping the edge of an adjacent section, a rotary shaft, series of gears attached to said shaft, series of racks having their outer ends pivotally connected with the corners of said wall sections respectively and having their inner portions meshing with corresponding ones of said gears, another series of racks having their outer ends pivotally connected with the lapped portions of said wall sections respectively and having their inner portions meshing with corresponding ones of said gears, guides for all of said racks, and mechanism for rotating said shaft and thereby said gears to move said racks longitudinally and thereby move said wall sections outwardly and inwardly and support said wall sections from distortion in all positions thereof, and means in connection with said shaft for defining the thickness of a wall molded about said form. 90 95 100 105

3. A form comprising a series of angular wall sections assembled in approximately rectangular form and each having its edges lapping the edges of an adjacent section, a rotary shaft extending axially through the form provided by said sections as aforesaid, 115 series of gears on said shaft, racks having their inner ends meshing with said gears and their outer ends connected with the corners of said sections respectively, other racks having their inner ends meshing with certain of said gears and their outer ends pivotally connected with lapping portions of said wall sections respectively, and mechanism for rotating said shaft to move said racks and thereby move said wall sections to different 120 125 adjustments to provide forms of different sizes and to support said wall sections undistorted in all of said positions. 130

JOHN K. GOIN.
